UNITED STATES PATENT OFFICE.

FRANK E. PAYNE, OF GLENCOE, ILLINOIS.

METHOD OF PACKING CONDENSERS.

1,387,901.

Specification of Letters Patent. Patented Aug. 16, 1921.

Application filed April 24, 1920. Serial No. 376,300.

To all whom it may concern:

Be it known that I, FRANK E. PAYNE, a citizen of the United States, residing at Glencoe, in the county of Cook and State 5 of Illinois, have invented certain new and useful Improvements in Methods of Packing Condensers, of which the following is a specification.

My invention relates to improvements in 10 methods of packing condensers, evaporators, and the like.

Heretofore, it has been necessary to renew the tubes of condensers and the like at intervals because of their disintegration due 15 to electrolysis. Since the larger condensers may contain several thousand tubes, it is apparent that the time, difficulty and expense of such renewal are important items of maintenance. Furthermore, packing is used at 20 each end of each tube to prevent leakage and the renewal of the tubes involves also a renewal of the packings.

The general object of the invention is to provide an improved method of packing condensers, which greatly reduces the detrimental effect of electrolysis thereby cutting down the renewal expense, and which makes 25 more rapid and effective such renewals as are required.

Contributory objects are to provide a 30 metallic bond between the tubes and the tube sheet thus furnishing a conducting path for such currents as are generated; to provide a bond of this character which permits 35 the necessary movements of the tubes, caused by expansion and contraction, without permitting leakage of air, vapor or liquid; and to provide a joint of this kind into which the metal packing may be readily packed 40 and from which it may be conveniently removed.

Other objects and advantages will be apparent from the following more detailed description.

For convenience, I have illustrated the invention as applied to a condenser, although 45 it is applicable to other classes of service, particularly where a high vacuum is to be maintained.

In the drawings—

Figure 1 is an elevation partly in section of a condenser.

Fig. 2 is an enlarged sectional elevation 50 of the tube sheet showing the connection of one of the tubes therewith.

Fig. 3 is a front elevation thereof.

Fig. 4 is a perspective view of one of the metallic packing rings.

Fig. 5 is a section of a modified joint between the tube sheet and the tube, and 60

Fig. 6 is a partial elevation of a modified tube structure.

The condenser 1 shown in Fig. 1 is intended to represent a standard construction as far as the relation of the tubes and the tube 65 sheet is concerned. The end of each tube 2 passes through an opening in the tube sheet 3, outward movement of said tube being limited by a ferrule 4, which has screw-threaded engagement with the wall of the opening. 70 Said ferrule has an open outer end to permit the water to flow therethrough and is also provided with a pair of notches 5 to receive a tool by means of which it may be screwed into position. 75

The inner end of the opening through the tube sheet is of reduced diameter, thereby providing a shoulder 6. An annular space is thus formed between said shoulder and the inner screw-threaded end of the ferrule. 80 This opening receives the packing, which heretofore has been made of some form of fabric. There is a slight clearance between the tube and the metal wall of the tube sheet and of the ferrule, a steam and water-tight 85 joint being maintained as far as possible with the fabric packing. Difficulty has been encountered, however, in that electrolytic action is usually set up, resulting in disintegration of the tubes near the joint and 90 further difficulty has been encountered in that the alkalis and other chemicals, which are often found in solution in the cooling water, cause deterioration of the fabric packings. Such packings also deteriorate under 95 the action of steam, oil and high temperatures. The high temperature frequently causes the packings to become hard or cement themselves to the tube preventing free movement of the latter as they expand and 100 contract due to temperature variations, resulting sometimes in buckling of the tubes.

I avoid these difficulties by using a metallic packing made preferably of a soft metallic substance which is not attacked by any 105 of the chemicals commonly occurring in circulating water and which does not deteriorate when exposed to high temperatures. Such packing, in the form of a divided or incomplete ring 7, is shown in Fig. 4 and 110

may consist of metal foil wound spirally back and forth on a suitable core and thereafter bent into a ring, or the ring may be made of crimped metal foil or otherwise formed. The packing described in Crane Patent 1,151,344, August 24, 1915, is suitable for this purpose. Such metal rings are more readily put in place in the annular recess surrounding the tube than the fabric packings and they are readily deformed by tightening the ferrule 4 as a result of which they expand laterally and form a water, air and steam-tight joint at the same time permitting the tube to slide freely when it expands or contracts, without impairing the high vacuum.

In Fig. 2 two such metallic packing rings are shown, although the number may be varied to meet different requirements.

An important advantage of the metallic packing rings is that a path of low resistance is provided through said rings, thereby forming a direct electrical connection between the tubes and the tube sheets. As a result of any small voltages developed, the current will flow through the metallic rings rather than from the tube through the circulating water or electrolyte, which latter flow is believed to be the cause of the tube disintegration previously experienced. To provide a path of good conductivity, the packing need not necessarily be all metallic. In fact, any packing having a conducting outer coating will answer the purpose, if it is otherwise satisfactory.

In Fig. 5 I have illustrated a modified construction wherein the ferrules are eliminated. The tube sheet 8 has an opening therethrough, part of which is in the form of a conical recess with an inclined wall 9, at the end of which is a shoulder 10. The tube 11, as in the first case illustrated, passes freely through the opening and has an extension of reduced diameter at its end forming a shoulder 12. The packing rings 13 are slipped into place and then expanded one at a time by being struck or swaged with a suitable tool such as described in a co-pending application of Julian N. Walton, Serial No. 378569, filed May 3rd, 1920. The packing is locked in place between the shoulder 10 and the sloping wall 9, thereby eliminating the ferrule while affording all the advantages of the construction previously described. The shoulder 12 limits the outer movement of the tube at one end and a similar shoulder at the opposite end limits its movement in the opposite direction, the movement being occasioned by expansion and contraction.

In Fig. 6 a further modified tube 14 is shown, the notches at the end of which are formed by bending outwardly the lugs 15, said lugs serving to limit the inward movement of one end of the tube and hence the

outward movement of the other end thereof and avoiding the necessity of the shoulder illustrated in Fig. 5.

The use of the metallic packing described permits a high vacuum to be maintained and at the same time permits the tube end to slide within the packing. In fact, the tube may be completely withdrawn without removing the packing in case the removable ferrule is used.

Inasmuch as some of the larger condensers in present-day use contain as many as twelve thousand tubes requiring twenty-four thousand sets of packings, it will be evident that the saving of time and money involved in cutting down renewals either of the packings or of the tubes is a very important matter. Not only may the packing be readily installed, but it may also be readily removed by means of a suitable removing tool also illustrated in said Walton application and it is more permanent than fabric packings and may be maintained steam and water tight by simply tightening the ferrules from time to time, if necessary.

The invention is not limited to the apparatus specified, but may be used in other types of equipment. In referring to air-tight joints in the claims, I intend to cover joints tight against leakage of vapor and liquid as well and, in fact, against leakage of whatever medium may be accessible to the joint.

What I claim is:—

1. Means for preventing deleterious electrolytic action, which consists in the combination in a receptacle, of a metallic tube sheet having openings therein, tubes having ends received within said openings, and metallic packing between said tubes and tube sheet forming an air-tight sliding joint and providing a path of low electrical resistance between said tube and sheet.

2. Means for preventing deleterious electrolytic action which consists in the combination in a receptacle, of a metallic tube sheet having openings therein, tubes having ends received within said openings, metallic packing between said tubes and tube sheet forming an air-tight sliding joint and providing a path of good electrical conductivity between said tube and sheet, and means for limiting the longitudinal movement of said tubes caused by temperature changes.

3. Means for preventing deleterious electrolytic action which consists in the combination with an electrically conductive tube sheet having an opening therein, of an electrically conductive tube passing therethrough, an enlarged annular recess forming part of said opening, and metallic packing rings compressed within said recess to form an air-tight joint and to electrically connect said tube and sheet.

4. The combination with a tube sheet hav-

ing an opening therein, of a tube passing therethrough and terminating near the outer plane of said sheet, an enlarged annular recess forming part of said opening, metallic packing rings individually compressed within said recess to form an air-tight joint and to electrically connect said tube and sheet, and means for maintaining the end of said tube near said outer plane as it moves under the influence of temperature changes.

5. The combination with a tube sheet having a conical opening therein with a shoulder at the inner end thereof, of a tube passing through said opening, and flexible metallic packing rings confined between said shoulder and the conical wall of said recess, said tube being formed to engage said packing to limit the longitudinal movement of said tube.

10. 6. A condenser comprising tube sheets having openings therein and a plurality of tubes having their opposite ends received within corresponding openings, each opening having an enlarged conical recess and divided metallic packing rings compressed within each recess to short circuit said tubes and sheets, and to provide an air-tight sliding joint, said packing being locked in place by the conical walls of the containing recess.

15. 7. In a condenser, a tube sheet having an opening with an enlarged annular portion, a tube passing loosely through said opening and having a reduced end portion to form a shoulder, and packing fitted within said enlarged opening and embracing said tube, said shoulder serving to limit the longitudi-

nal movement of said tube by engaging said packing, the latter comprising metal foil wound helically on a core.

20. 8. A method of packing condensers and the like to prevent deleterious electrolytic action, which consists in supporting the end of the tube within an opening in the tube sheet by metallic packing which maintains an air tight sliding joint and electrically short circuits the tube and sheet.

25. 9. The combination with a tube sheet having an opening therein, of a tube passing therethrough and terminating near the outer plane of said sheet, an enlarged annular recess forming part of said opening, John Crane packing compressed within said recess to form an air-tight joint and to electrically connect said tube and sheet, and means for maintaining the end of said tube near said outer plane as its moves under the influence of temperature changes.

30. 10. A device of the class described, comprising metallic tube sheets and metallic tubes connecting the same and in communication with openings in said tube sheets, said tubes being in metallic contact with one tube sheet near one of their ends and having metallic packings between their other ends and the other tube sheet, said packings forming air-tight sliding joints and furnishing paths of good electrical conductivity, thereby substantially eliminating deleterious electrolytic action.

35. In testimony whereof, I have subscribed my name.

FRANK E. PAYNE.
